UNITED STATES PATENT OFFICE.

HAMILTON T. HOWELL, OF WOODSIDE, NEW YORK, ASSIGNOR TO BLACK & BOYD
MANUFACTURING COMPANY, OF NEW YORK, N. Y., A CORPORATION OF NEW YORK.

DESIGN FOR AN ELECTROLIER.

43,535.

Specification for Design.

Patented Feb. 11, 1913.

Application filed April 10, 1912. Serial No. 689,915. Term of patent 3½ years.

To all whom it may concern:

Be it known that I, HAMILTON T. HOWELL, a citizen of the United States, and a resident of Woodside, county of Queens, city and State of New York, have invented a new, original, and ornamental Design for an Electrolier, of which the following is a specification, reference being had to the accompanying drawing, forming a part thereof.

In the drawing, Figure 1 represents a side elevation of an electrolier, showing my new design, and Fig. 2 is a plan view of the same.

The design comprises a body of a number of diverging, ornamental members, with a centrally located ornamental protuberance, and with the lamp sockets at the ends of the members.

I claim:

The ornamental design for an electrolier, as shown and described.

HAMILTON T. HOWELL.
